APPARATUS FOR TRANSFERRING FLUIDS

James B. Hunter, Upper Darby, Robert C. Taylor, Melrose Park, and William S. Young, Philadelphia, Pa., assignors to Consolidated Engineering Corporation, Pasadena, Calif., a corporation of California

Application January 28, 1946, Serial No. 643,942

10 Claims. (Cl. 137—78)

1

This invention is concerned with the transfer of light fluids, both liquid and gaseous, from one container to another and provides novel means for effecting such transfer while maintaining a seal at the transfer point to prevent the influx of atmospheric contaminants, etc.

In analytical apparatus such as mass spectrometers and infra-red spectrometers, fluids to be analyzed should be introduced into the sampling system of the apparatus without introducing a contaminant, such as air. Heretofore this has been accomplished through valves, stop cocks, and the like, but such devices are not entirely satisfactory. The moving parts of valves, etc. present an opportunity for leakage, and lubricants employed to seal the moving parts may contaminate the sample or absorb part of it.

A co-pending application Serial No. 642,376, filed January 19, 1946, now Patent No. 2,452,623, issued November 2, 1948, describes and claims a system for sample introduction involving no moving parts. However, this system is suitable only for the introduction of liquids and does not serve when gaseous samples are to be introduced. In accordance with the present invention, any light fluid, be it gaseous or liquid, may be transferred from one container to another while maintaining a seal between the two. This is accomplished by providing a seal composed of a porous member that is pervious to the light fluid to be introduced but impervious to a heavy liquid (say, mercury) in which the light fluid is substantially insoluble and immiscible. The porous member is attached to a conduit or container into which the light fluid is to pass and is covered at its opposite face with a pool of heavy liquid. The light liquid to be transferred is placed in another container provided with a second porous member having characteristics similar to that of the first, i. e. it is pervious to the light liquid but impervious to the heavy liquid. The second porous member is so constructed that it may be brought into contact with the first member within the pool so as to displace the heavy liquid between the two members and permit the flow of the fluid between the two members, means for reducing the pressure between the two members being provided to induce such flow.

The second porous member may be retained in the pool covering the first porous member but out of contact with the latter. Or the second porous member may be placed in an auxiliary well and covered therein with a second pool of the heavy liquid. If this well is attached to the second member and is smaller than that in which

2

the first porous member is disposed, it may be inserted into the larger well and contact thus made between the two members.

Mercury is, in most instances, a suitable heavy liquid since aqueous solutions and many organic liquids are substantially insoluble in it.

The porous members may be made of any suitable material. Disks made by sintering together small siliceous particles are desirable, care being taken to control the size of the pores.

These and other aspects of the invention will be apparent upon consideration of the following detailed description taken in conjunction with the accompanying drawings, in which:

15 Fig. 1 is a sectional elevation through a preferred form of my invention in which the entire sample container may be immersed in a well of the heavy fluid;

Fig. 2 is a sectional elevation of a modification 20 of the apparatus of Fig. 1 in which the porous member attached to the sample container communicates therewith through a connection which permits the sample container per se to remain outside the well;

25 Fig. 3 is a sectional elevation of another type of the apparatus of my invention in which the porous member of the sample container is provided with a removable auxiliary well for heavy fluid;

Fig. 4 is a section through the apparatus of 30 Fig. 3 taken along the line 4—4; and

Fig. 5 illustrates a cap for use with the sample container of Fig. 3.

Referring to Fig. 1, it will be seen that the 35 apparatus comprises a well 10 in the general form of a test tube with an enlarged upper section 11. A pool 12 of heavy liquid, such as mercury, is contained in the well with its upper surface adjacent the top thereof.

40 A sample conduit 13 projects downwardly into the upper portion of the well and its lower end is closed by means of a porous disk 15 made by sintering together particles of glass. The disk is below the surface of the pool at all times.

45 A sample container 16, in the general form of a test tube that is shorter and of smaller diameter than the well, is provided. As shown in Fig. 1, it is disposed in the well itself.

The sample container or tube is provided with 50 a filling tube 17 attached to its upper side wall and extending vertically upward. As shown in Fig. 1, the upper end of this tube is sealed.

A second porous disk 18 corresponding in diameter to the interior diameter of the sample tube is fastened across the mouth of the sample

tube slightly below its upper edge. This disk is likewise made of small particles of glass sintered together. The portion of the sample tube extending above the second disk comprises an auxiliary well 19.

The use of the apparatus of Fig. 1 is as follows:

With the sample container removed from the well, it is evacuated through the filling tube while it is held vertically, with a small pool of mercury overlying its porous disk, so as to form a seal. When the tube has been evacuated, a sample of light fluid, say a gas sample, is introduced into the container and the filling tube is sealed, for example by means of a flame in the usual laboratory tube-sealing procedure, while the sample tube is chilled to condense the sample in the lower portion of the sample tube.

The sealed sample container may be stored indefinitely in an upright position so that its porous disk remains covered by the mercury pool.

When it is desired to introduce the sample into an analytical apparatus, say a mass spectrometer, the sample container at approximately room temperature is lowered into the pool and then raised so that the two porous disks 15, 18 come in contact with each other. Suction applied to the conduit 13 will cause the sample, say a light hydrocarbon gas, to be sucked up through the two disks into the conduit and thence to the analytical apparatus (not shown), while the mercury of the pool seals the apparatus from the atmosphere.

The apparatus of Fig. 2 comprises the well 10 having the enlarged upper section 11 and containing the mercury pool 12. The sample conduit 13 is similar to that of Fig. 1 and is provided with a similar porous glass disk 15 attached to its lower end under the mercury pool.

The sample container of Fig. 2 differs from that of Fig. 1 in that it is a relatively large glass bulb 20 having a vertical filling tube 21 attached at its upper end. A freezing-out tube 22 projects downwardly from the bottom of the container. It has a side branch 23 extending horizontally approximately midway down the tube. The side branch turns upward into a vertical section 24 which contains a porous disk 25. This disk is disposed slightly below the top of the tube to provide an auxiliary well 26.

The use of the apparatus of Fig. 2 is in general similar to that of Fig. 1. The sample container is evacuated through the filling tube; the sample is admitted through the filling tube; the container is refrigerated, say by bringing it into contact with liquid nitrogen or the like, to cause any gases to liquefy and pass into the freezing-out tube. The filling tube is then sealed with a flame.

The filling and freezing-out operations are conducted with the apparatus held in a vertical position so that the porous disk remains covered by a pool of liquid mercury in the well 26.

The sample in the container may be stored indefinitely. When an analysis is to be conducted, the container is disposed as shown in Fig. 2 with the two porous disks in contact with each other, and suction is applied to the tube 13 to cause part of the contents of the container to be withdrawn through the two porous disks.

In the apparatus of Figs. 1 and 2, the well 10 and withdrawal tube 13 preferably remain stationary while the sample container with its attached seal is moved. In the apparatus of Figs. 3, 4 and 5, it is convenient to keep the sample

container stationary while moving the suction conduit and its attached seal. Referring to the latter figures, it will be seen that the sample container 30 is an upright bulb of glass or the like with a freezing-out tube 31 on its lower end and an upwardly projecting neck 32. A filling tube 33 is connected to the side of the neck and projects upward. The porous disk 34 is fastened in the neck slightly below its mouth to provide a well 35 overlying the porous disk and containing a pool of mercury.

A sample withdrawal conduit 36 of relatively large diameter projects through a stopper 37 of glass or the like and is sealed thereto. The lower end 38 of the sample withdrawal tube is of relatively small diameter and is sealed at its lower end by a small porous disk 39 of sintered glass. An auxiliary well or cup 40 is attached to an upwardly projecting rod 41 that passes between a set of guides 42, 43 formed integrally with the upper portion of the withdrawal tube. A helical spring 44 holds the rod to the side of the tube and it permits the rod to be slid upwardly and downwardly with respect thereto and also to be rotated so that the auxiliary well can be turned away from the lower end of the tube with its sintered disk. As shown in Fig. 5, the withdrawal tube is kept sealed when not in use by placing the auxiliary well around the lower end of the tube, thus covering the sintered disk with a pool of mercury 45 retained in the well.

The use of the apparatus of Figs. 3 to 5 is as follows:

The container 30 is filled with a gas sample as described for the previous cases and the filling tube is flame-sealed after the sample has been frozen out. To withdraw gas from the container, the end of the withdrawal tube is inserted into the well 35 with the auxiliary well 40 covering its end. The auxiliary well is then rotated and raised out of the pool 35 and the two sintered disks are brought in contact with each other. If suction is applied to the withdrawal tube, gas from the container will pass through the two sintered disks into the withdrawal tube and thence to the analysis apparatus (not shown).

To protect the withdrawal tube and its attendant apparatus from damage when it is not in use, a cap 50 in the general form of a test tube is provided. This cap has a neck 51 into which the stopper 37 fits.

The withdrawal tube should be maintained in a substantially vertical position at all times so as to keep its end sealed.

The three types of apparatus just described preferably are constructed entirely of glass, save for the helical spring 44 and, of course, the mercury pools. The large sintered disks 18, 25, 34 may be commercial 10 mm. sintered glass disks or "immersion filters" of "fine" porosity. These disks should be covered at all times with mercury to a depth of about 10 mm. to prevent the entrance of air into the vessel.

The small sintered disks 39, 15 are not available commercially but may be made in the laboratory as follows:

Pieces of Pyrex glass tubing are thoroughly crushed in a mortar, or by other suitable means. The portion of the glass particles passing through a 300 or 325 mesh sieve is collected for use. A mold is prepared by drilling a hole 3 to 4 cm. deep in a small carbon block. A glass tube in the end of which the disk is to be attached is ground down to a sharp tapered edge. A small quantity of the powdered glass is then placed on

a flat surface and the tapered end of the glass tube is pressed into the pile. A close-fitting glass rod is inserted into the top of the tube and the powdered glass is tamped into the tapered end until a packed layer about 2 mm. deep is formed. The tube is then carefully transferred, tapered end down, to the carbon mold, care being taken not to disturb the loosely consolidated particles of glass tamped in the end. After transfer, the powdered glass is given a final tamping with the glass rod and the mold containing the tube and its contained glass particles is placed in a muffle furnace and held at approximately 1800° F. for several minutes or until the protruding portion of the glass tube sags to an almost horizontal position. The mold is then removed from the furnace and allowed to cool. Thereafter the tube is removed from the mold.

It will be found that the powdered glass has sintered together but that it has shrunk away from the glass tube slightly. To effect a tight seal between disk and tube, a carbon rod is drilled with a tapered hole large enough to allow the sintered end of the glass tube to just enter. The glass tube is then cut off and sealed to a short length of larger tubing which acts as a handle, and the carbon rod containing the tapered hole is heated with a torch to a red heat. The flame is then removed, and the sintered disk and tube are quickly pressed into the hole and rapidly rotated. This swages the glass tube around the sintered disk and provides a tight seal.

To test the seal, the open end of the tube is connected to a vacuum system and the sintered disk immersed in mercury. If no mercury leaks through when the tube is substantially completely evacuated, it is satisfactory in this respect. The tube is then removed from the mercury. If air now leaks through the disk into the vacuum system, it is sufficiently porous for use.

Heating time, the amount of swaging, and the glass particle size distribution are factors in the determination of final porosity.

The manufacture of the additional parts of the apparatus is conducted by standard glass blowing procedures.

The apparatus has been described as applied to the sampling of gases and it will find its principal utility in this field. However, it may be adapted for use with light liquids. For example, the apparatus of Fig. 2 may be used to transfer liquids from the container 20 into the conduit 13, provided that there is a sufficient amount of liquid in the container to provide a slight head on the two sintered disks when they are placed together.

All three types of the apparatus described have been found exceedingly useful in the transfer of gas samples into various types of analytical apparatus, including both infra-red and mass spectrometers. The mercury maintains a thoroughly tight seal around the two disks and, if the manipulation is properly conducted, there is substantially no danger of leakage from the outside.

We claim:

1. In apparatus for transferring a relatively light fluid, the combination which comprises a conduit, a well, a pool of heavy liquid in which the light fluid is substantially insoluble and immiscible disposed in the well, a porous member communicating with the conduit and covered by the pool and pervious to the light fluid but impervious to the heavy liquid, a container for the light fluid provided with a second porous member having characteristics similar to the first member, the second porous member being so connected

to the container that it may be brought in contact with the first member in the pool and permit the flow of the fluid from the container into the conduit through the two members, auxiliary means for sealing the second porous member when it is disposed outside the pool, and means for producing a pressure differential between the container and the conduit to induce such flow.

2. Apparatus according to claim 1 in which the auxiliary sealing means comprises a second well disposed above and attached to the second porous member, and a second pool of the heavy liquid in the second well covering the second porous member, the second well being small enough to fit in the first well.

3. In apparatus for transferring a relatively light fluid, the combination which comprises a conduit, a main well, a pool in the main well of heavy liquid in which the light fluid is substantially insoluble and immiscible, a porous member communicating with the conduit and covered by the pool and pervious to the light fluid but impervious to the heavy liquid, a container for the light fluid provided with a second porous member of characteristics similar to those of the first, an auxiliary well disposed above and attached to the second porous member, an auxiliary pool of the heavy liquid in the auxiliary well, the latter being small enough to permit the second porous member to be brought in contact with the first member in the main pool and permit the flow of the fluid from the container into the conduit through the two members, and means for producing a pressure differential between the container and the conduit to induce such flow.

4. Apparatus according to claim 3 in which the second porous member is mounted on the top of the container in the auxiliary well.

5. Apparatus according to claim 3 in which the second porous member and the attendant auxiliary well are connected to the container by a tube adjacent the lower portion of the container.

6. Apparatus according to claim 3 in which the heavy liquid is mercury.

7. Apparatus according to claim 3 in which the porous members are composed of siliceous particles sintered together.

8. In apparatus for transferring a relatively light fluid, the combination which comprises a conduit, a container for the light fluid, a first porous member forming an opening in the container pervious to the light fluid, a second porous member also pervious to be light fluid and disposed in the end of the conduit, one of said porous members forming the bottom of a well, a pool of heavy liquid in which the light fluid is substantially insoluble and immiscible disposed in the well, the two porous members being impervious to the heavy liquid and being adapted to be brought in contact with each other in the pool, auxiliary means for sealing the other of said porous members when it is disposed outside the pool, and means for producing a pressure differential between the container and the conduit when the two porous members are in contact within the pool.

9. In apparatus for transferring a relatively light fluid the combination which comprises a conduit, a first porous member forming an end of the conduit and pervious to the light fluid, a container for the light fluid having a filling tube adapted to be sealed when the container is filled with light fluid and a tubular opening, a second porous member disposed across the tubular opening and spaced from an open end thereof to form

a first well, a pool of heavy liquid in which the light fluid is substantially insoluble and immiscible disposed in the first well, the two porous members being impervious to the heavy liquid, the end of the conduit being insertable in the pool so as to bring the first and second porous members in contact within the pool, means for producing a pressure differential between the container and conduit to induce flow of light fluid from the container into the conduit through the porous members, and a second independent well filled with the heavy liquid and adapted to seal the first porous member when the first porous member is removed from the first well.

10. Apparatus according to claim 9 wherein the

second well comprises a cup having an elongated support arm secured to the conduit in rotatable and longitudinally slideable relationship.
